UNITED STATES PATENT OFFICE

152,903

DESIGN FOR A COIN OPERATED COMBINATION PHONOGRAPH AND TELEVISION CABINET

Frank Principe, New York, N. Y.

Application August 22, 1947, Serial No. 141,000

Term of patent 7 years

(Cl. D56—4)

To all whom it may concern:

Be it known that I, Frank Principe, a citizen of the United States of America and resident of New York, county and State of New York, have invented a new, original, and ornamental Design for a Coin Operated Combination Phonograph and Television Cabinet, of which the following is a specification, reference being had to the accompanying drawing, forming a part thereof.

The single figure of the drawing is a front isometric view of a coin operated combination phonograph and television cabinet, showing my new design.

The front of the cabinet itself is substantially

symmetrical with respect to a central vertical plane.

I claim:

The ornamental design for a coin operated combination phonograph and television cabinet, substantially as shown and described.

FRANK PRINCIPPE.
